UNITED STATES PATENT OFFICE.

CARL ANDERSEN AND AAGE CHRISTIAN SYLVEST, OF COPENHAGEN, DENMARK.

SOUND DISTRIBUTOR.

Application filed August 13, 1924. Serial No. 731,824.

To all whom it may concern:

Be it known that we, CARL ANDERSEN and AAGE CHRISTIAN SYLVEST, citizens of Denmark, and both residing at Kobmagergade 59, Copenhagen, Denmark, have invented certain new and useful Improvements in Sound Distributors, of which the following is a specification.

The invention relates to a sound distributor, especially for radio telephony, by means of which the sound emitted from the diaphragm of one or two listening telephones may be distributed uniformly to a relatively large number of persons, and may 15 be reinforced at the same time.

The apparatus is mainly characterized in that the sound from the telephones is projected towards the point of a cone which is disposed within a hollow body made of 20 ebonite, or the like. From the cavity of said body hoses extend in all directions by way of which the reinforced sound is directed to the ears of the various persons, and in this manner the sound in its entirety 25 is distributed in perfectly uniform and regular manner to all the listeners.

The apparatus may be varied considerably in detail, and one construction is illustrated on the drawing, in which—

30 Fig. 1 shows the apparatus mainly in vertical section and

Fig. 2 the same in cross-section along the line A—B in Fig. 1.

In the construction illustrated, use is made 35 of a hollow body 1, open at both ends and consisting of ebonite, caoutchouc or some other suitable material and being adapted to be placed vertically as shown, or else horizontally or in some other desired direction.

40 In the cavity of this body there is attached in suitable manner a massive body made similarly of ebonite, wood or other hard material, having at its centre a cylindrical portion 2 and tapering at both ends 45 into a cone point 3 nearly reaching the end of the body 1, a cavity 4 being formed between each of these cones and the cylindrical portion 2.

From each of the cavities of the body 1 50 radial channels are extending, into which the tubes 6 connected to the distributing hoses 5 may be inserted. As shown in Fig. 1 the said tubes are expanded funnel-wise toward the cavity in order to be better 55 adapted to catch the sound. At the opposite end of each hose there is provided a suitable

hook-shaped nozzle 7 with a suitable shaped head 8 the rear edge of which is fitted with a recess 9 in order to fit firmly into the ear.

In case not all the hoses 6 are being used, 60 a plug 10 may be inserted into the corresponding radial channels, in such manner that the cavity remains closed.

In an apparatus of this kind with two cavities and two circular rows of distributing hoses use is also made of two ordinary listening telephones 11, which are placed in such a manner tightly against the open ends 65 of the body 1 that their diaphragms will be placed immediately against the cavities and 70 the cones 3.

In order to keep the telephones pressed tightly against the body 1 the entire device may be firmly supported in a frame consisting of two end plates 12 and rods 13 connecting the same, one of the end plates eventually forming a base for the apparatus as shown. 75

The attachment of the parts may be effected by means of nuts 14 and wing nuts 80 15, which are provided on the ends of the rods 13 outside of the plates 12.

In the said plates there is formed a central opening 16 for passage for the cord connection of the telephone, if the former is disposed on the back side of the telephone. 85

Besides there are provided openings 17 in the plate 12 adapted to accommodate adjusting knobs 18, which may be provided on the back of the telephone. As shown in Fig. 1, 90 a packing ring 19 of soft rubber may be inserted between the listening telephone and the body 1 in order to prevent the loss of any portion of the sound.

The frame may be of other suitable shape 95 than the one shown, and instead of using such a frame the listening telephones and the extreme portions of the body 1 may be fitted, as shown underneath in Fig. 1, with corresponding screw threads 20, so that the 100 parts may be screwed together, any special devices for holding the parts together being thus rendered superfluous.

The projecting cones in the cavity of the body 1 form good distributing members 105 for the sound, while the cavities 4 provide resonance, in such a manner that the sound is not only distributed uniformly to all the listeners, but is also reinforced in the said cavities. As the latter are made absolutely tight, the entire sound will be distributed uniformly to all sides, and may be 110

heard distinctly and clearly by up to twenty persons.

Instead of being constructed for two telephones, the apparatus may of course be made for a single one, so that there is provided only one distributing cone and one single row of hoses 5.

The body 1 may be of polygonal outside shape instead of being cylindrical. Besides the tubes 6 as well as the plugs 10 may be so hollowed at their inner end, that their end faces will fit the cylinder wall of the cavity.

Having now described our invention, what we claim is:

1. In an apparatus for reinforcing and distributing the sound from two telephones each having a diaphragm, a distributing cone facing each diaphragm, a hollow body 20 in which said cone is arranged and fixed in front of the diaphragm of each telephone.
2. In an apparatus for reinforcing and distributing the sound from two telephones,

each having a diaphragm, a distributing cone facing the diaphragm, a hollow body 25 in which said cone is arranged and fixed in front of the diaphragm of each telephone, packing rings between said hollow body and said telephones and an adjustable frame forming a base for the apparatus and in 30 which said diaphragms and hollow body are arranged, said frame serving to press said diaphragms against the ends of said hollow body.

3. In an apparatus for reinforcing and 35 distributing the sound from two telephones, each having a diaphragm, a distributing cone, a hollow body in which said cone is arranged and fixed in front of the diaphragm of each telephone, said hollow body and said 40 telephones having screw threads by means of which the parts are interconnected.

In witness whereof we affix our signatures.

CARL ANDERSEN.

AAGE CHRISTIAN SYLVEST.
